United States Patent Office

Des. 224,851

Patented Sept. 26, 1972

224,851

SHEET OR SIMILAR ARTICLE OF BED LINEN

John W. Rock, Wyckoff, N.J., assignor to Cannon Mills
Company, Kannapolis, N.C.

Filed Feb. 16, 1971, Ser. No. 115,924

Term of patent 14 years

Int. Cl. D16—13

U.S. Cl. D92—26

F17-1

FIG. 2

FIG. 1 is a top plan view of a sheet or similar article showing my new design, a design unit being shown within the broken lines, which unit repeats in regular succession beyond the unit boundaries; and

FIG. 2 is an enlarged top plan view of the design unit. I claim:

The ornamental design for a sheet or similar article of bed linen, substantially as shown and described.
